UNITED STATES PATENT OFFICE.

HENRI PIERRE LAURENT LAUSSUCQ, OF READING, PENNSYLVANIA.

BENDING MACHINE.

Application filed November 4, 1926. Serial No. 146,137.

My invention relates to bending presses of the type intended to operate upon heavy material and in which one end may be opened for convenient use for removal of the finished work.

A purpose of my invention is to operate a closure for the open end of a bending press by mechanical means.

A further purpose is to lock a closure by power-operated means preferably by rotary movement caused by plunger operation.

A further purpose is to interlock the locking mechanism for a power-operated closure at the open end of a bending press with the closure and with operating mechanism for the main press.

Further purposes will appear in the specification and in the claims.

I have preferred to illustrate my invention by one form only, selecting a form which has proved to be practical, highly efficient and very satisfactory, and which at the same time well illustrates the principles of my invention.

Figure 1 is an end elevation of my preferred form.

Figure 2 is a side elevation of the structure seen in Figure 1, taken from the right-hand side of that view.

Figure 3 is a top plan view of the structure seen in Figures 1 and 2, omitting some of the parts.

Figure 4 is an end elevation, partly sectioned, to show the detail of part of the operating mechanism.

Figure 5 is a fragmentary longitudinal section through the upper beam corresponding with a portion of Figure 4 and with line 5-5 on Figure 6.

Figure 6 is a section taken upon line 6-6 of Figure 5.

Figure 7 is a section upon line 7-7 of Figure 6.

In the drawings similar numerals indicate like parts.

In open end bending presses provision has already been made for holding the upper beam at the open end by a link or closure.

My invention is directed primarily to the power operation of this closure, the locking of the closure in position and the interlocking of the devices by which these two functions and press operation are performed so as to operate reliably and to the best advantage.

The bed 5 of the press supports a main or

stationary standard 6 upon which the upper or fixed beam 7 of the press is secured. This standard is not only of great strength but its surfaces 8 and 9 of engagement with the base and fixed beam 7 are extensive in a direction parallel to the paper in Figure 1 so as to support the beam as much as possible against tilting strains due to the weight of the beam when the closure is open. It is united to the bed and beam and is aligned by bolts 10 and 11 but the main reliance for the tensile strain upon the beam is placed upon through bolts 12 extending from the bottom of the bed to the top of the beam on opposite sides of the beam.

The upper or stationary beam carries a die 13 and the bed supports cylinders 14 in which operate plungers 15 connected by a lower platen 16 to which are attached end guides 17. The lower beam carries a die not shown and a table 18 adapted for support of the work and in which I have shown rolls 19.

The cylinders 14 are fed hydraulically through pipe 20 from any suitable supply (not shown) which is controlled by valve 21 operated by lever 22 pivoted at 23. The valve stems are shown at 24 and 25. As far as described this structure is not novel and the parts and their functions require no further explanation.

The ends of the lower beam or platen travel along guides 26 carried respectively by the standard and by a side frame 27 secured to the main frame.

The beam 7 terminates at its open end in a stem 28 which receives and is held against vertical movement by the link 29 swinging about a pivot 30. The pivot rests at spaced points in ears 31 upon side frame 27. This frame is held in place by bolts 32 passing through to the lower part of the bed and there held by nuts 33 and by bolts 34, 34' at the sides and end.

The upper surface 35 of the stem 28 and the under surface 36 at the top of the opening 37 within the link 29 slope downwardly and outwardly just enough to allow the link to swing over the nose of the stem and not enough to cause any opening movement when they are tightened by the upward pull of this end of the fixed platen in use.

In order that the link may be lifted to the position seen in Figure 4, or lowered therefrom to open position, I provide a thrust bar 38 operated by hydraulic cylinder 39 through plunger 40 and cross-head 41. The

bar is pivoted at one end at 42 in ears 43 upon the link 29, and at the other end upon a pin 44 carried by ears 45 rigid with the cross-head. The slides for the cross-head 5 are shown at 46.

Suitable glanding is, of course, provided for the plungers in this cylinder and in the other cylinders shown.

The operation of the plunger within the 10 cylinder 39 swings the link closure 29 upon its pivot and closes or opens the link upon or from the stem of beam 7.

In order to protect against displacement of the link 29 from its proper position upon 15 the stem 28 I lock it there, showing one convenient method of doing this.

As best seen in Figures 5, 6 and 7 the stem 28 is provided with steep mutilated threads of the breech block type comprising annularly arranged alternating segmental threads 47 and spaces 48. The spaces permit annularly arranged inwardly projecting segmental threads 49 upon the interior of the locking ring 50 to pass axially of the thread during 20 swinging movement of the link closure. Spaces 51 alternate with the threads 49 so that relatively the threads 47 pass through these spaces.

The ring 50 is provided with external 30 teeth 52 and is supported to provide rotarial movement by guides 53, 54. A removable plate 55 upon the front of the link and spaced from the body of the link supports the structure against movement to the right 35 in Figure 5.

When the link closure has been thrown to the position shown in Figures 5 and 6 the ring 50 is turned a distance corresponding approximately with the segmental length of 40 the threads to interlock the threads of the link with the threads of the stem and is correspondingly turned in the opposite direction to release this locking engagement. This is accomplished by a rack 56 operated 45 by a stem 57, connected with a plunger 58, located in hydraulic cylinder 59. The rack is supported against lateral movement by guides 60, 61 and 62 and is shown as provided with wear plates 63.

50 The cylinder 59 is fed by valve 64 through interconnecting pipes 65 and 66 and the valve receives its fluid supply through pipe 67 and exhausts freely to the atmosphere. The cylinder 59, valve 64 and pipe connections all swing with the link closure and therefore must be so connected as to be capable of performing their several functions notwithstanding movement of the link closure.

55 The supply pipe 67 receives its fluid pressure from a pipe 68 coaxial with the pivot of the link closure and can therefore easily be maintained in connection with this supply by any of a number of joints well known and 60 generally used in the hydraulic art to main-

tain connection between relatively swinging parts. Pipe 68 is fed through a supply pipe 68' as hereinafter indicated.

I connect the valve stem 69 with a plunger 70 by any suitable thrust connection such as 70 straps 71. The plunger extends through an opening 72 in casing 73 nearly to the bottom of the casing and beyond the axis 74 of rotation of the link. The opening 72 passes clear through the casing and at its upper 75 end is counterbored at 75 to receive a collar 76 upon the plunger. It also receives a spring 77 which presses downwardly upon the collar and is seated at its upper end at 78.

In closed position of the link closure, the lower end 79 of the plunger 70 and the lower part of the opening 72 are in line with a plunger 80 which in this position of the parts can be pushed into the opening to 85 press plunger 70 upwardly against the pressure of spring 77 to operate the valve 64.

The upward movement of plunger 80 is limited by a collar 81 and the plunger is supported by a spring 82 pressing against 90 the collar at its upper end and seated at 83. The spring pressure is intended to substantially counterbalance the weight of that part of the operating mechanism for the plunger 80 which is suspended from the plunger. 95 These parts are the plunger 80, straps 84, bell crank 85 and an adjacent part of rod 86, by which connection is made from the operating lever 87 to lift and lower the plunger 80. This mechanism should be 100 over-counterbalanced to give plunger 80 a tendency to lie in raised position.

Because of the fact that the plunger 80 cannot be raised until the end of the opening 72 swings in line with it, the lever 87 can not 105 be thrown all of the way unless the link closure is in closed position. However, the lever 87 engages or abuts a stop 88' upon the lever 88 by which the valve 69 controls fluid pressure and exhaust in cylinder 110 89.

Because of the interlinkage between lever 87 controlling the locking operation and lever 88 controlling the turning of the link lever, lever 88 can not be thrown to open the 115 link until lever 87 has been thrown to release the locking engagement between the link and the stem 28. For the same reason the lever 87 can not be thrown fully to locking position until the lever 88 is fully home in 120 position to close the link upon the stem.

The lever 87 carries a toe 90 beyond its pivot point 91 which toe controls movement of lever 22 interlocking with it to prevent 125 shifting of lever 22 and the consequent operation of the main plungers except when the locking lever 87 is in locking position as shown.

In operation, with the parts in the position shown in Figures 2 and 4 the lever 87 is 130

thrown to the left in Figure 2 withdrawing plunger 80 from the opening in the casing and permitting the retractive spring to throw plunger 70 so as to operate valve 64 and through it to operate the plunger in cylinder 59. The locking ring 48 is thus rotated sufficiently to release the lock. The removal of plunger 80 from the casing permits the casing to turn along with the link closure. Movement of the lever 87 also permits operation of the lever 88 to the left, operating valve 89 and plunger 40 so as to swing the locking link from the position shown to a position nearly perpendicular to it, in which the end of the upper beam or platen is open.

Reverse movement of the lever 88 throws the plunger 41 to turn the link closure into closed position, after which lever 87 is thrown to the right to force the plunger 80 into the casing so as to lift the plunger 70 and operate the locking mechanism. Lever 22 can not be thrown to put pressure on the main cylinders except when lever 87 is in the position shown.

The closing, locking and several interlocking mechanisms have been shown in detail in order to comply with the statute requiring disclosure of the best means known to me for carrying out my invention but without intending to restrict to the forms of mechanism by which they are performed.

In view of my invention and disclosure variations and modifications to meet individual whim or particular need will doubtless become evident to others skilled in the art, to obtain part or all of the benefits of my invention without copying the structure shown, and I, therefore, claim all such in so far as they fall within the reasonable spirit and scope of my invention.

Having thus described my invention, what I claim as new and desire to secure by Letters Patent is:

1. In a bending press, a press frame including upper and lower beams adapted to be open at one end and bending mechanism cooperating with one of the beams, in combination with a link pivotally connected with one of the beams, a plunger-operated thrust device engaging the link to throw it over the other beam, and rotary locking mechanism for holding the link to the other beam.

2. In a bending press, a press frame including upper and lower beams adapted to be open at one end, a link pivotally connected with one of the beams, a plunger-operated thrust device engaging the link to throw it over the other beam and plunger-operated locking mechanism for holding the link to the other beam.

3. In a bending press, a press frame including upper and lower beams adapted to be open at one end, a link pivotally connect-

ed with one of the beams, a plunger-operated thrust device engaging the link to throw it over the other beam, plunger-operated locking mechanism for holding the link safely to the beam and connection between the device and mechanism to throw them in predetermined order.

4. In a bending press, a press frame including upper and lower beams adapted to be open at one end, in combination with a link pivotally connected with one beam, a plunger-operated thrust device engaging the link to throw it over the other beam and a mutilated thread breech block, interlocking connection between the movable end of the link and the beam.

5. A bending press having a frame, upper and lower fixed beams closed at one end and adapted to be open at the other, a movable platen, hydraulic means for moving the platen, a swinging link for closing the open end, an hydraulically-operated thrust device engaging the link to swing it, rotary locking connections between the free end of the link and the one beam, a rack and pinion connection for rotating the locking mechanism and hydraulic cylinder and plunger means for moving the rack.

6. A bending press having a frame, upper and lower fixed beams closed at one end and adapted to be open at the other, a movable platen, hydraulic means for moving the platen, a swinging link for closing the open end, plunger-operated thrust bearings engaging the link to lift and lower it, rotary locking connections between the free end of the link and the one beam, a rack and pinion connection for rotating the locking mechanism, hydraulic cylinder and plunger means for moving the rack and interlocking between the connections for operating the two plungers controlling the sequence of link movement and locking and unlocking operations.

7. A bending press having a frame, upper and lower fixed beams closed at one end and adapted to be open at the other, a movable platen, a swinging link for closing the open end, a plunger-operated thrust bearing engaging the link to lift and lower it, rotary locking connections between the free end of the link and the one beam, a rack and pinion connection for rotating the locking mechanism, hydraulic cylinder and plunger means for moving the rack, a valve controlling the cylinder for the second plunger, connections for operation of the valve and means for throwing the connections in line and thus making them operative when the link is closed and out of line and inoperative when the link is opened.

8. In an open-end bending press, upper and lower beams open at one end, a movable platen, hydraulic means for moving the

platens, hydraulically-operated closing and locking mechanisms for the open end, separate connections for operating them, both valve operated, a lever controlling one of the valves to close the open end, a connection between the lever for closing the end and the valve controlling the locking, permitting movement of the lever when the end is closed and preventing the movement when the end is open.

9. An open end bending press, in combination with a swinging closure for the press, and locking mechanism therefor, an hydraulic cylinder and connections for throwing the closing mechanism, a lever controlling operation of this cylinder, an hydraulic cylinder and connections for operating the locking mechanism, a valve and valve rod controlling operation of this cylinder and an interconnection between the valve rod and the operating lever for the closing cylinder, operative by reason of the valve rod lying in line with the interlocking connection when the end is closed.

10. In an open end bending press, a swinging closure for the press, means for operating the closure, a rotary lock for the closure, an hydraulic cylinder and plunger and connections for operating the lock, a valve controlling the hydraulic cylinder, a valve rod extending down from the valve past the pivot for the swinging closure, a casing guiding the rod and open in line with it beyond the center about which the closure swings and operating means about which the closure swings adapted to fit into the opening in the closure in closed position of the closure and to operate the locking mechanism.

11. In an open end bending press, a swinging closure for the press, means for operating the closure, a rotary lock for the closure, an hydraulic cylinder and plunger and connec-

tions for operating the lock, a valve controlling the hydraulic cylinder, a valve rod extending down from the valve across the pivot for the swinging closure, a casing guiding the rod and open in line with it beyond the center about which the closure swings, operating means movable across the axis about which the closure swings and adapted to fit into the opening in the closure when the latter is in closed position to operate the locking mechanism and counterbalancing for the movable parts.

12. In a bending press having an open end, a link closure for the open end, a pivot for the closure at the lower end of the link and a breech block type lock holding the link in place.

13. An open end bending press, in combination with a link closure for the open end and a lock for the link closure operative in the closed position and inoperative in open position of the link closure.

14. In an open end bending press, upper and lower beams open at one end, hydraulic press-operating means, closing mechanism for the open end and locking devices for the closing mechanism interlocking with the press-operating means.

15. In an open end bending press, upper and lower beams open at one end, hydraulic press-operating means, power-operated closing mechanism for the open end and power-operated locking devices for the closing mechanism.

16. In an open end bending press, upper and lower beams open at one end, hydraulic press-operating means, power-operated closing mechanisms for the open end and power-operated locking devices for the closing mechanism interlocking with the closing mechanism.

HENRI PIERRE LAURENT LAUSSUCQ.
